RIDING MOWER

Donald E. Dailey, Vanderburgh County, Ind., assignor to
Hahn, Inc., Evansville, Ind., a corporation of Indiana

Filed Mar. 23, 1962, Ser. No. 69,390

Term of patent 14 years

(Cl. D40—1)

Des. 197,728

PAGE 2

FIG. 2

Des. 197,728

PAGE 3

FIG. 3

FIG. 4

FIG. 1 is a view in side elevation of a riding mower embodying my new design, the opposite side being essentially the same as the side shown except for the grass discharge;

FIG. 2 is a front elevational view thereof;

FIG. 3 is a rear elevational view thereof; and,

FIG. 4 is a top plan view thereof.

I claim:

The ornamental design for a riding mower, as shown and described.
